(57) **CLAIM**

The ornamental design for an eyeglasses holder, as shown and described.

DESCRIPTION

FIG. 1 is a perspective view of an eyeglass holder showing my new design;

FIG. 2 is a front elevational view thereof; the eyeglasses being shown in broken lines to illustrate the use, and forming no part of the claim;

FIG. 3 is a rear elevational view thereof;

FIG. 4 is a top plan view thereof;

FIG. 5 is a bottom plan view thereof; and,

FIG. 6 is a left side elevational view thereof, the right side being a mirror image.
